UNITED STATES PATENT OFFICE.

ALBERT GOULD JENNINGS, OF NEW YORK, N. Y.

DESIGN FOR A FACE-VEIL.

41,903.

Specification for Design.

Patented Nov. 7, 1911.

Application filed June 7, 1911. Serial No. 631,870. Term of patent 7 years.

To all whom it may concern:

Be it known that I, ALBERT G. JENNINGS, a citizen of the United States, and a resident of the city of New York, borough of Manhattan, in the county and State of New York, have invented a new, original, and ornamental Design for Face-Veils, of which the following is a specification, reference being had to the accompanying drawing, forming part thereof.

The figure is a plan view of a face veil showing my new design.

I claim—

The ornamental design for a face veil as shown in the accompanying drawings.

ALBERT GOULD JENNINGS.

Witnesses:

WALTER L. SACKETT,
L. A. MACKEY.
